UNITED STATES PATENT OFFICE

2,470,238

SHUFFLEBOARD-BILLIARD TABLE WITH
REPLACEABLE TOPErnest Correale and Joseph Correale,
Jersey City, N. J.

Application May 9, 1946, Serial No. 668,402

1 Claim. (Cl. 273—6)

1

This invention relates to new and useful improvements in tables for games, and has more particular reference to a shuffleboard-billiard table.

The new shuffleboard-billiard table resembles a billiard table except for the construction of the table top. In a billiard table the top consists of a plate of slate which is covered with felt. In the new table, in accordance with this invention, the top is similar to the playing top of a shuffleboard. It is constructed from laminated wood and is highly polished and waxed so that the customary shuffleboard weights may slide on it.

It is proposed to characterize the new shuffleboard and billiard table by the fact that it includes a rectangular frame provided with a head wall, a foot wall, and side walls. It is proposed to mount rails on the top edges of said walls. These rails are provided with diamonds for indicating a head spot, a foot spot, a center spot, a head string, a foot string, and a center string. Rebound cushions for shuffleboard weights are mounted on the inner faces of said walls beneath said rails. A shuffleboard-like top is mounted across and through openings in said side walls and beneath said rebound cushions. The shuffleboard-like top is releasably locked in position.

A feature of the new table construction resides in the fact that the shuffleboard-like top may be removed, and placed back into position with its bottom face up, or other similar shuffleboard-like tops may be substituted for it. Because of this construction it is possible to imprint different game faces on the faces of the shuffleboard-like tops so that the table may be used to play different games. Many well-known games may be played on the new table and they are too numerous to list here, but for illustrative purposes some of the games which may be played are as follows: "keeno," "darts," "billiards two or three cushion," "bottle pool," "bowling," "baseball," "chinee or janpenee," "bagatell," "barilli," "regular pool," "rotation pool or Chicago," "poker stud or draw," "lotto," "checkers," etc.

Two different forms of the shuffleboard-billiard table have been disclosed in this specification. The first form resembles the usual carom billiard table, while the second form resembles a pocket billiard table. Each of these forms embody the essential features of this invention.

Another object of the invention is the construction of a device as described which is simple and durable and which may be manufactured and sold at a reasonable cost.

For further comprehension of the invention,

and of the objects and advantages thereof, reference will be had to the following description and accompanying drawings, and to the appended claims in which the various novel features of the invention are more particularly set forth.

5 In the accompanying drawings forming a material part of this disclosure:

Fig. 1 is a plan view of a shuffleboard-billiard table constructed in accordance with this invention.

10 Fig. 2 is a side elevational view of the table shown in Fig. 1.

Fig. 3 is a fragmentary enlarged vertical sectional view taken on the line 3—3 of Fig. 1.

15 Fig. 4 is a fragmentary horizontal sectional view taken on the line 4—4 of Fig. 3.

Fig. 5 is a plan view of another shuffleboard-billiard table constructed in accordance with a modified form of this invention.

20 Fig. 6 is a fragmentary enlarged vertical sectional view taken on the line 6—6 of Fig. 5.

Fig. 7 is a fragmentary horizontal sectional view taken on the line 7—7 of Fig. 6.

The shuffleboard-billiard table, in accordance with that form of the invention illustrated in Figs. 1—4, inclusive, includes a rectangular frame 10 provided with a head wall 11, a foot wall 12 and side walls 13. Rails 14 are mounted on the top edges of said walls 11, 12 and 13. The inner

30 edge portions of these rails project inwards of the inner faces of said walls. The rails 14 are provided with diamonds 15 for indicating a head spot, a foot spot, a center spot, a head string, a foot string, and a center string in accordance with the rules of pocket and carom billiard games.

35 Rebound cushions 16 for shuffleboard weights are mounted upon the inner faces of the walls 11, 12 and 13 beneath the rails 14. These rebound cushions are illustrated set into grooves 17 formed upon the inner faces of said walls. The rebound cushions 16 include base strips 18 upon which rubber strips 19 are mounted. A felt covering 20 is engaged around the front, and top and bottom sides of the strips 18 and 19.

40 45 A shuffleboard-like top 22 is mounted across and through openings 23 formed in the side walls 13. The shuffleboard-like top 22 is mounted beneath the rebound cushions 16. The shuffleboard-like top 22 is constructed from a plurality

50 of laminated boards 24 connected together in the usual way used in constructing shuffleboard tops. The openings 23, in the side walls 13, are of rectangular construction for receiving the shuffleboard-like top 22 in the fashion of the drawer

55 of a table or deck. The side laminations 25 of

the shuffleboard-like top 22 are just as thick as the thickness of the walls 13. Preferably, these side boards 25 have their outer faces ornamented to simulate the side faces of the rectangular frame 10.

The rectangular frame 10 is supported by legs 26. These legs are attached to the frame with brackets 27. The legs 26 are provided with adjustable feet 28 by which the shuffleboard-billiard table may be adjusted to a level position. The shuffleboard-like top 22 is associated with means for releasably locking it in position on the frame 10. The specific means illustrated on the drawing includes a lug 28 mounted on each bracket 27 and supporting a clamp screw 29 which is adapted to engage against the bottom face of the shuffleboard-like top 22 and force it against the tops of the openings 23 to clamp and hold the shuffleboard-like top 22 releasably in position.

The operation and use of the new shuffleboard-billiard table may be understood from the following:

Any number of games may be played on the table with the usual shuffleboard weights. These weights may be slid over the polished and waxed top face of the shuffleboard-like top 22 so as to engage the rebound cushions 16 in accordance with various rules of various games. The top and bottom faces of the shuffleboard-like top 22 may be imprinted with the board markings or notations of various games. One or more, or a series of shuffleboard-like tops 22 may be purchased with each table. The clamp screws 29 may be loosened and then the shuffleboard-like top 22 may be slipped out, as for example, schematically indicated by the dot and dash lines 22' in Fig. 1. In this way the top may be completely removed and then re-inserted with its bottom face up, or a different top may be inserted in its place. The clamp screws 29 are then re-engaged to firmly lock the top in position.

In Figs. 5-7, inclusive, a modified form of the invention has been disclosed which is very similar to the prior form, but distinguishing in several respects. This particular shuffleboard-billiard table is provided with a shuffleboard-like top 32 constructed from a plurality of shallow laminations 33 and a plywood bottom 34. This shuffleboard-like top 32 has deep side laminations 35 engaging into the openings 23 in the side walls 13 of the frame 10. The intention is to indicate that the shuffleboard-like top may be constructed in various ways. The top face of the shuffleboard-like top is imprinted with arcuate scratch lines 36 simulating the pockets of a pocket billiard table. The bottom face of the shuffleboard-like top 22 may be imprinted with the markings of other games.

This shuffleboard-billiard table is provided with top rails 37 which are mounted on the top edges of walls forming the frame 10. However, these top rails 37 are formed from separate sections which are spaced from each other so as not to

obstruct and conceal the pocket simulations 36. Rebound cushions 38 for shuffleboard weights are mounted on the inner faces of the walls of the frame 10 at points beneath the rails 37. The rebound cushions 38 are formed from sections which have their abutting ends 39 curved to simulate the pockets of a billiard table. These curved ends 39 are at locations within the arcuate scratches 36.

10 In other respects this form of the invention is identical to the previous form and like parts are indicated by like reference numerals.

The operation and use of this form of the invention is substantially identical to the prior form. This particular shuffleboard-billiard table may be used to play a number of the pocket billiard games. The shuffleboard-like top 32 may be replaced to play other types of games.

While we have illustrated and described the 20 preferred embodiments of our invention, it is to be understood that we do not limit ourselves to the precise constructions herein disclosed and the right is reserved to all changes and modifications coming within the scope of the invention 25 as defined in the appended claim.

Having thus described our invention, what we claim as new and desire to secure by United States Letters Patent is:

In a shuffleboard-billiard table having a frame provided with side walls, rebound cushions for shuffleboard weights mounted on the inner faces of said walls a short distance down from the top edge thereof, said side walls having openings through which a shuffleboard-like top may be engaged to a position a short distance beneath said rebound cushions, a shuffleboard-like top engaged in said position and extending across said frame and having its sides engaging into the said openings in said side walls, and means for releasably 30 forcing said shuffleboard-like top upwards so that its sides are clamped against the top faces of said openings in said side walls in order that said shuffleboard-like top does not work its way outwards of the openings in said side walls due to 35 vibrations while players throw shuffleboard weights across said shuffleboard-like top and against said rebound cushions.
